UNITED STATES PATENT OFFICE.

LO KA CHEUNG, OF CANTON, CHINA.

POLISHING-MACHINE.

1,257,951.

Specification of Letters Patent. Patented Feb. 26, 1918.

Application filed July 11, 1916. Serial No. 108,642.

To all whom it may concern:

Be it known that I, LO KA CHEUNG, a citizen of China, residing at Canton, China, have invented new and useful Improvements in Polishing-Machines, of which the following is a specification.

This invention relates to improvements in polishing machines and has particular application to a machine for polishing shoes, although I wish it to be understood, that my invention, in its useful application, may be employed for polishing silverware, brassware and other articles.

In carrying out my invention, I employ a brush capable of rotation and a polish container arranged above the brush and adapted to deliver polish to the brush, in combination with a polishing roll arranged adjacent to the brush and adapted to be rotated, and an electric motor or other suitable driving means connected to the brush and the polishing roll and to the polish container so that in the operation of the motor polish will be fed to the brush and the brush and roll revolved. Suitable means is also provided for disconnecting the polish container from the motor so that the brush and polishing roll may be rotated without feeding polish to the brush. The brush, the polish container and the polishing roll and the motor for operating all of such parts are inclosed in a suitable casing and supported in proper relative positions and the machine is small and compact and may be handled conveniently and easily so that the polishing operation may be carried on rapidly and with a minimum effort on the part of the operator.

My invention consists in the construction, combination and arrangement of parts hereinafter set forth in and falling within the scope of the claims.

In the accompanying drawings;

Figure 1 is a view in front elevation of a polishing machine constructed in accordance with the present invention.

Fig. 2 is an end view thereof.

Fig. 3 is a vertical sectional view through the machine, parts being shown in elevation.

Fig. 4 is a similar view taken at right angles to Fig. 3.

Fig. 5 is a like view taken on a plane parallel with Fig. 4 and looking in the opposite direction.

Fig. 6 is a horizontal sectional view on the line 6—6 of Fig. 3.

Figs. 7, 8, 9 and 10 are detail views of the invention.

Referring now to the drawings in detail, 60 1 designates a substantially rectangular vertical casing. Mounted upon the upper end of the casing is a removable cover 2 provided with a handle 3. In the present instance, one end edge of the cover 2 is 65 hinged to the corresponding end wall of the casing, while secured to the other side wall of the casing is a split button 4 and pivoted to the adjacent end wall of the cover is a disk 5 formed with an opening 6 adapted 70 to receive the button 4 so as to hold the cover 2 in closed position and enable the casing to be carried about by the handle 3 without swinging the cover to open position. The edge portion of the disk 5 opposite 75 from that portion connected to the cover is provided with a finger piece 7 whereby the disk may be swung to locking and unlocking positions and when the disk is swung to locking position the sections of the button 80 4 pass through the opening 6 and frictionally engage the opening to hold the disk in closed or locked position.

In the present instance, one side wall of the casing 1 is capable of removal from 85 the casing and the edges of the end walls corresponding to the edges of the removable side wall are flanged inwardly as at 8 and have the confronting edges thereof formed with longitudinal grooves 9 respectively and these grooves 9 receive the longitudinal edges of the removable side wall so that the side wall may be moved into and out of position so that access may be had to the interior of the casing. Se- 90 cured to the bottom wall of the receptacle 1 centrally thereof are vertical standards 10 arranged alongside of the respective side walls of the casing and terminat- 95 ing at a point approximately centrally of 100 the height of the casing. Journalled in the upper ends of the standards 10 is a shaft 11 and formed on the shaft 11 at a point approximately centrally thereof is a pinion 12, while surrounding the shaft 11 and fixed thereto adjacent to one end thereof is a relatively large pulley wheel 13. Suitably fastened to the bottom wall of the casing 1 at one side of the standards 10 is an electric motor 14 and fixed to one end of the arma- 110

ture shaft of the motor 14 is a pulley wheel 15 and trained over the pulley wheels 13 and 15 is an endless belt 16 whereby the motion will be transmitted from the armature 5 shaft to the shaft 11. Secured to one end wall of the casing and projecting into the latter above the motor 14 is a supporting plate 17 and mounted upon the supporting plate 17 is a dry cell 18. Mounted upon the 10 outer side of said end wall of the casing is an electric switch comprising, in the present instance, a strip 19 having one end bent at right angles to itself as at 20 and fastened to the casing is a contact stud 21 secured to 15 the casing and disposed in the path of movement of the other end of the strip. Passing through the strip 19 and bearing against the adjacent end wall of the casing is a pin 22 and threaded upon the pin 22 between the 20 casing and the strip is a thumb disk 23 which may be rotated to permit of adjustment. Normally, the pin 22 acts to hold the strip 19 spaced apart from the stud 21 and the end of the strip adjacent to the stud is 25 adapted to be forced into engagement therewith by means of the fingers. The contact stud 21 and the strip 19 are preferably insulated from the casing as shown in Fig. 3 of the drawings. One terminal of the dry 30 cell 19 is connected to the contact stud 21 by means of a conductor 24, while the other terminal is connected to one side of the motor by means of a conductor 25 and leading from the other side of the motor is a conductor 26 35 terminally connected to the contact strip 19. Thus, when the switch is actuated to closed position, the cell 19 is connected in circuit with the motor 14 and the latter operates to drive the disk 13 and the shaft 11.

40 Arranged upon the opposite side of the standards 10 is a polish container 27 adapted to collapse and expand after the fashion of a bellows. Secured to the upper end of the polish container 27 is a collar 28 and mounted upon the collar 28 is a plate 29 projecting beyond the edge of the collar and having the projecting portions thereof formed with openings. Passed through these openings are the upper ends of vertical guide rods 30 and the lower ends of the rods are secured to the bottom wall of the casing. These rods and the plate serve as guides for the container so as to facilitate the upward and downward movement thereof. Fixed to the plate 55 29 and extending upwardly therefrom is a guide frame 31 embracing bar 32, which bar has its edge formed with teeth 33 meshing with the pinion 12 on the shaft 11. Secured to the outer side of the rod or bar 32 is a 60 tube 34 formed with a vertical slot 35. 36 indicates a releasing rod having one end formed with a ball 37 arranged within the tube 34 and the other end projecting through the adjacent end wall of the casing and 65 threaded onto the projecting end of the rod 36 is a nut 37. Secured to the lower end of the polish container 27 is a cap 38 and the bottom wall of the cap 38 is formed with openings 39, while rotatably mounted upon the cap 38 and of a shape conforming to 70 that of the cap is a valve 40 provided with a handle 41 projecting through the end wall of the casing. The bottom wall of the valve 40 is formed with openings adapted to be moved into and out of registration with the 75 openings in the cap to control the discharge of the polish from the container. In the present instance, the plate 29 is formed with a filling opening 42 and pivoted upon the plate is a closure 43 movable to cover and 80 uncover the filling opening.

Secured to the bottom wall of the casing 1 and depending therefrom contiguous to the opposite side walls of the casing are hangers 44 arranged adjacent to one end wall of 85 the casing, while depending from the bottom wall of the casing contiguous to the respective side walls and arranged adjacent to the other end wall of the casing are hangers 45. Journaled in the lower ends of the hangers 44 is a shaft 46 upon which is rotatably mounted a brush 47, while journaled in the lower ends of the hangers 45 is a shaft 48 upon which is mounted a polishing roll 49. Keyed upon corresponding 95 ends of the shafts 46 and 48 are pulley wheels 50 and trained over these wheels is an endless belt 51, while fixed upon both ends of the shaft 48 are pulley wheels 52 and trained over the pulley wheels 52 and pulley wheels 53 on the respective ends of the armature shaft of the motor 14 are endless belts 54. By means of these belts 54 and 51, it will be seen that motion is transmitted from the armature shaft to the shaft 100 carrying the polishing roll and to the shaft carrying the brush, thereby rotating the polishing roll and the brush.

In practice, the circuit closer is actuated to connect the motor to the dry cell and in 110 the operation of the motor motion is transmitted from the armature shaft to the pulley wheel 13, thereby revolving the pulley wheel and the shaft 11 and in the rotation of the shaft 11, the pinion 12 meshing with 115 the rack teeth 33 on bar 32 slides the bar and the plate 29 downwardly so that the polish may be discharged from the container 27 through the registering openings in the cap 38 and valve 40 onto the brush 47. 120 Simultaneously with the feeding of the polish onto the brush, motion is transmitted from the motor to the polishing roll 49 and the brush 47 and the polish may be applied to the article by means of the brush 125 47 and then the article polished by means of the polishing roll 49.

When the machine is not in use, the brush and the polishing roll are preferably enclosed by means of a cover 55 adapted to be 130

slipped over the lower end of the casing and having the ends thereof equipped with locking devices identical in construction with the locking device for the cover 2.

5. After a sufficient quantity of polish has been delivered to the brush 47 and it is desired to operate the brush and the polishing roll without delivering more polish to the brush, the members 32 and 34 may be moved 10 outwardly to disengage the rack teeth 33 from the pinion 12 by means of the releasing rod 36.

15. While I have herein shown and described one preferred form of my invention by way of illustration, I wish it to be understood that I do not limit or confine myself to the precise details of construction herein described and delineated, as modification and variation may be made within the scope of 20 the claims and without departing from the spirit of the invention.

I claim:

25. 1. In a device of the class described, a polishing roll, a brush for applying polish, means for driving said brush and roll, a polish container formed with flexible and collapsible walls, the lower end of said container including a cap provided with apertures, a valve member also provided with apertures and arranged to inclose the cap, vertical guide members for the collapsible receptacle, a transversely extending device carried by the upper portion of the receptacle and coöperating with the guide members, a rack member extending from said transverse member, and means engaging the rack member, said means having motion imparted thereto by the aforesaid driving means.

40. 2. In a device of the class described, a polishing roll, a brush for applying polish, means for driving said brush and roll,

a vertically arranged polish receptacle located above the polish applying brush and including flexible and collapsible walls, the 45 lower portion of said receptacle including an apertured cap, a valve member provided with apertures and adapted to inclose said cap, a transverse member extending across the upper end of the receptacle, guiding 50 means at the sides of said receptacle, said transverse member coöperating with the guiding means, additional guiding means located above the receptacle, a device co-operating therewith, said device carrying a 55 series of teeth, a pinion meshing with said teeth, and means for actuating the pinion from the aforesaid driving means.

3. In a device of the class described, a brush, means for driving said brush, a polish receptacle mounted above the brush and including flexible and collapsible walls forming a bellows-like construction, a cap connected with the lower end of the flexible walls and provided with apertures, a rotatable flanged member provided with apertures and inclosing said cap, a collar carried by the upper portion of the receptacle, a transverse member secured thereto, a plurality of vertical guides with which said 65 transverse member coöperates, a pinion, means for actuating the pinion, and a rack bar mounted vertically above the transverse member and movable laterally with reference thereto into position for engaging the 70 pinion and being actuated thereby for moving the transverse member and receptacle.

75. In testimony whereof I affix my signature in presence of two witnesses.

LO KA CHEUNG.
